(57) **CLAIM**

The ornamental design for a spoon, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top front perspective view of a spoon;

FIG. 2 is a front view of FIG. 1;

FIG. 3 is a rear view of FIG. 1;

FIG. 4 is a left view of FIG. 1;

FIG. 5 is a right view of FIG. 1;

FIG. 6 is a top view of FIG. 1;

FIG. 7 is a bottom view of FIG. 1;

FIG. 8 is a front left perspective view of an upper part of the spoon;

FIG. 9 is a front view of FIG. 8;

FIG. 10 is a rear view of FIG. 8;

FIG. 11 is a left view of FIG. 8;

FIG. 12 is a right view of FIG. 8;

FIG. 13 is a top view of FIG. 8;

FIG. 14 is a bottom view of FIG. 8;

FIG. 15 is a bottom front perspective view of an handle of the spoon;

FIG. 16 is a front view of FIG. 15;

FIG. 17 is a rear view of FIG. 15;

FIG. 18 is a left view of FIG. 15;

FIG. 19 is a right view of FIG. 15;

FIG. 20 is a top view of FIG. 15; and,

FIG. 21 is a bottom view of FIG. 15.
